UNITED STATES PATENT OFFICE.

THOMAS ELLIOTT, OF CINCINNATI, OHIO, ASSIGNOR TO THE CINCINNATI CAR COMPANY, OF WINTON PLACE, OHIO, A CORPORATION OF OHIO.

RAILWAY CAR.

Application filed January 8, 1925. Serial No. 1,162.

To all whom it may concern:

Be it known that I, THOMAS ELLIOTT, a citizen of the United States, residing at Cincinnati, in the county of Hamilton and 5 State of Ohio, have invented certain new and useful Improvements in Railway Cars, of which the following is a specification, reference being had therein to the accompanying drawing.

10 This invention relates to improvements in railway cars, more particularly cars of the types used on city and interurban rail-ways.

15 The object of this invention is to pro- vide a slidable door made in sections hinged or flexibly connected together. The purpose of the flexible connections is to make the door readily assume the curvature of that part of the car where the doorway is located, so that the door will promptly con- 20 form to the general outline of that part of the car wall; and will also straighten out when it is run back from the doorway into the pocket in the straight side of the car 25 wall.

Another feature is that of a guard con- 30 nected with the door and adapted when the door is in the doorway to extend over the step-well and across the space between the floor and the door to prevent anyone from stepping down into this space and being injured.

35 In the accompanying drawings forming a part of this specification:

Figure 1 is a partial plan and partial horizontal sectional view of that part of a car embodying my invention.

40 Figure 2 is a vertical, transverse sectional view, on a larger scale, taken on the line 2-2 of Figure 1, looking in the direction of the arrow.

45 Figure 3 is an enlarged detail view, in horizontal section, of parts of two sections of the door showing the hinge connection between them, and the division between two sections of the guard.

50 Figure 4 is a vertical sectional view taken through the upper part of one of the doors and the roof structure.

55 Certain conventional parts of an ordinary car are shown in the drawings, particularly Figure 1, and somewhat in Figure 2, which form no part of this invention. For instance, such parts are the vestibule corner post 1 and the structural features

adjacent to it as shown at the right in Figure 1; and such also as the other structural features appearing at the left in Figure 1 and consisting generally of the parts 2, 3 and 4, the latter being a cross partition 60 which divides the interior of the car from the platform where the doorway is located.

A pocket indicated at 5 is formed within the side wall of the car. Inner sashes 6 are built in and outer wall plates 7 and one or more sashes 8 are utilized in forming the car body, with the space or pocket 5 between them as seen in Figure 1. The door is to be run back into this pocket when the doorway is to be opened by the removal of 70 the door. The doorway extends from the vestibule post 1 back to the beginning of the side wall of the car, as also seen in Figure 1. The door is made in sections 9, 10 and 11 or other suitable number. These sections are flexibly or hingedly connected together. The preferred type of connec- 75 tion or hinge is shown best in Figure 3 and consists of a hinge proper formed of plates 12 and 13 secured to the faces of the door sections as by screws 14 and having a pintle 15. This results in making the door as a whole flexible or bendable where the sections come together, so that the door will readily assume a curvature conforming 80 substantially to the curvature of the outline of the platform, and yet will straighten out to conform to the straight sided pocket 85 into which the door recedes when the doorway is to stand open.

90 Any convenient means of suspending the door, as by a track and rollers may be used, a selected form of which is indicated clearly in Figure 4. The track is designated 16, the hangers which are connected with the door sections are indicated at 18, and the rollers at 19. They are mounted on the hangers and are adapted to travel on the track.

100 In my co-pending application, Serial No. 746,032, filed October 27th, 1924, I have shown and described hand operated means for actuating car doors, and I would state that that mechanism is entirely applicable to the doors which enter into the present 105 invention for purposes of opening and closing them.

110 And in my other co-pending application, Ser. No. 753,405, filed Dec. 7, 1924, I have shown power operated mechanism for open-

ing and closing car doors and I wish it to be understood that such power mechanism may also be employed in connection with the doors of the present invention.

5 It will now be seen that the several sections of my present door conform themselves, as to whether they assume together a curved line or a straight line or in part a straight and in part a curved line, 10 to the curvature of the platform and the straight lines of the pocket, so that the door as a whole may readily be moved from across the doorway into the pocket, more or less, or wholly, and from the pocket 15 across the doorway also more or less or wholly, without any binding or sticking and with smoothness and readiness. Thus my door arrangement constitutes a combination of a flexible door with a curved doorway 20 and a straight sided pocket.

In order to prevent accident or injury to passengers who might otherwise step into the space between the edge of the platform and the inner face of the door when the latter is closed, I provide a guard indicated at 25 and best seen in Figure 2. It will be seen that this guard is attached at 21 to the door sections and is itself made in sections as shown in Figure 3 so that it will conform 30 to the position of the door sections, whether they form a straight line or a curved line. And it will further be seen, from Figure 2 that the guard extends laterally from the door toward the floor 22 of the platform 35 and thus overlaps the space between the door and such edge, so that each section of the guard will effectually prevent a passenger getting his foot into the space between the door and the platform and down into the 40 step-well 23 which is beneath the door. In order to cover the gap between the sections of the guard I further provide lap-strips 20^a, each secured as by rivets to one guard near its end so as to overlap the next section and cover the space between them. In 45 Figure 3 I have shown the lap-strip broken away to exhibit the space between the guards. This guard made in sections and coordinated with my doors also made in 50 sections and adapted to travel on curved lines, constitutes an improvement over the rigid guard set forth in my Patent No. 1,476,960, dated December 11, 1923, for railway cars.

55 In order to guide the lower end of the door as also the guard sections I provide at

one or both ends of the step-well a guide roller 24 mounted on a stud carried by a clip 25 secured to the end plate of the step-well. These features are seen in Figure 2.

60

It will now be seen that the features of my invention provide for the ready self-alignment of the door with the curvature of the edge of the platform floor and with the straight line sides or enclosures of the pocket; and also that the guard likewise conforms itself as a whole to the curved and straight positions of the door itself.

65

It will be understood that I desire to comprehend within my invention such modifications as may be necessary to adapt it to varying conditions and uses.

70

Having thus fully described my invention, what I claim as new and desire to secure by Letters Patent of the United States, is:

75

1. In a car, the combination with a side wall having a pocket and a platform having a doorway, of a door mounted to slide from the pocket to the doorway and vice versa and composed of sections flexibly connected together, and a guard made in sections and connected each to a section of the door.

80

2. In a car, the combination with a side wall having a straight sided pocket and a platform having a curved doorway, of a door made of sections hinged together and adapted to travel from the pocket to the doorway and vice versa and to conform itself from a straight line to a curved line and vice versa, and a guard made in straight sections and connected each to a section of the door.

85

3. In a car, the combination with a side wall having a pocket and a platform having a doorway, of a door made in sections hingedly connected together, a track on which the door is hung, a guard composed of sections each secured to a section of the door, the guard sections extending across the space between the door and the platform, and means to guide the lower end of the door by contact with the guard.

90

4. In a car, a door composed of sections hingedly connected together, and a guard secured to the door, made in sections connected respectively to the respective door sections, and extending laterally from the door so as to occupy the space between the door and the floor of a car when the door and guard are mounted in place in such car.

95

In testimony whereof, I affix my signature.

THOMAS ELLIOTT.
